KNITTING MACHINE

Frank G. Weisbecker, Glenside, Pa., assignor to
Arcadia Hosiery Co., Lansdale, Pa., a corpora-
tion of Pennsylvania

Application July 9, 1938, Serial No. 218,448

25 Claims. (Cl. 66—126)

This invention relates to improvements in knitting machines, and more particularly to improvements in the yarn carriers of straight knitting machines.

5 In straight knitting machines, such as those which are now commonly used in the production of full-fashioned hosiery, the yarn to be knit is laid along the sinkers and dividers by selectively reciprocated yarn carriers. A number of 10 different forms of such yarn carriers are shown by my prior Patents Nos. 2,014,341, dated September 10, 1935; 2,026,514, dated December 31, 1935; and 2,201,801, dated December 7, 1937.

The present invention provides a number of 15 novel features for knitting machine yarn carriers, for example, of the type shown in said patents. This invention provides a novel support for a yarn carrier guide tube. It also provides means for detachably connecting a yielding or 20 resilient yarn guide to the supporting arm of its carrier and thereby facilitating repair or replacement of the yielding guide as occasion requires. Another novel feature involves an arrangement of 25 yarn carrier guide tubes which simplifies their assembly in a yarn carrier, as well as their replacement.

Straight knitting machines, according to the more common practice, comprise a number of 30 knitting sections, which operate simultaneously to produce a like number of stocking blanks or parts thereof. Each of these knitting sections includes a number (usually 6 or 7) of yarn carriers, which are selectively operated as desired. These 35 yarn carriers are reciprocated in the space between the needles and sinker bed of the respective knitting section to lay the yarn on the sinkers and dividers. A common practice is to so support and reciprocate the yarn carriers that they travel different paths and avoid interference with each 40 other. As a result, one of the yarn carriers travels closer to the sinker bed than do the other yarn carriers. In fact one of the yarn carriers, the one to which reference has just been made, usually has its lower end actually riding on the 45 adjacent surface of the sinker bed during yarn laying operations. This contact with the sinker bed rapidly wears away the conventional yarn carrier and soon destroys its usefulness.

The early destruction of yarn carriers by the 50 sinker beds is avoided by the present invention, which provides a novel form of yarn carrier for riding a sinker bed. This novel yarn carrier will have a relatively long useful life and will continue to operate in desired manner for an indefinite 55 period even though the sinker bed is constantly engaged during yarn laying operations.

It is, therefore, one object of this invention to provide a knitting machine yarn carrier with a novel support for its yarn guide means.

60 A further object is to provide a knitting ma-

chine yarn carrier with a readily replaceable yarn guide.

Another object is to provide a novel yarn carrier of the type having a yielding or flexible yarn guide tube.

Another object is to provide a knitting machine yarn carrier with a removable yarn guide of the type which may yield when it strikes an obstruction during yarn laying operations.

A further object is to provide a knitting machine yarn carrier with a novel arrangement of 10 yarn guide tubes.

A still further object is to provide an improved knitting machine yarn carrier of the type which rides a sinker bed during operation.

Other objects of this invention will appear from the following description, the appended claims, and the accompanying drawing, which illustrates two embodiments of this invention.

In the drawing, Figure I is a perspective view 20 of a yarn carrier embodying this invention.

Figure II is a transverse cross-section view through a portion of a conventional straight knitting machine and shows the yarn carrier of Figure I riding the sinker bed.

Figure III is a cross-sectional view taken on line III—III of Figure II.

Figure IV is an exploded view of the parts which are assembled to form the structure of Figure III.

Figure V is a front elevational view of a further embodiment of this invention.

Referring now in detail to the drawing, Figure II shows certain conventional machine parts which are helpful to an understanding of this 35 invention. These conventional parts are the sinker bed 1, the verge plate 2, the sinker 3, and the needle 4. A yarn carrier 10 embodying this invention is illustrated in Figure II in position for riding the sinker bed 1. In yarn laying operations, the yarn carrier 10 is reciprocated along a path normal to the plane of the accompanying sheet of drawing and constantly engages the front surface of the sinker bed 1 as shown in Figure II.

To avoid wear on the supporting arm 11 of the 45 yarn carrier 10 as the latter rides the sinker bed 1, the lower end of the yarn carrier supporting arm 11 is provided on its rear side with a protective plate 12. This plate 12 may be formed of any 50 suitable material, although it preferably is formed of relatively thin, resilient sheet metal. The plate 12 preferably should be of such character as to retain its original shape without support and to serve efficiently in its capacity as a 55 protective means. The plate 12 also is preferably as thin as these requirements permit, in order that the lower end of the yarn carrier supporting arm 11 may be maintained as close to the sinker bed as possible and thereby leave available, for 60

the other yarn carriers of the same knitting section during their movement, as much space as possible between the sinker bed 1 and the needles 4.

5 The metal, where such is used, for the plate 12 is preferably steel which has been tempered to make it relatively soft and resilient. Experience shows that a protective plate 12 of such metal is well suited to the requirements of any 10 yarn carrier 10 which rides the sinker bed 1. In some straight knitting machines, each knitting section has two yarn carriers which ride the sinker bed at different times. Each of these 15 two yarn carriers may be provided with a protective plate 12. Other materials which might be used for the plate 12 include hard rubber, Bakelite, and porcelain. If the chosen material is steel, the plate 12 may be welded to the supporting arm 11. The plate 12, however, may be 20 secured in place by soldering, gluing, vulcanizing or in other suitable manner depending on the kind of material of which the plate 12 is formed.

For reasons explained hereinafter, the lower 25 portion of the plate 12 may extend beyond the end of the supporting arm 11 and have a centrally disposed cut-out area 13 as shown in Figures I to IV. In order to provide sufficient strength and thereby avoid accidental deformation or breakage, the lower plate portion may 30 be made relatively wide, preferably wider than the lower end of the supporting arm 11 (see Fig. III).

The yarn (not shown) being supplied by the 35 yarn carrier 10 passes along a groove 14 in the upper side of the supporting arm 11 and then through a set of tubes 15, 16 and 17.

From groove 14, the yarn (not shown) passes first into the yarn guide tube 15. This tube 40 15 has a flared upper end portion 18, and is received within a socket 19 provided in the supporting arm 11. To assemble the tube 15 and the supporting arm 11, the former is placed in the groove 14, aligned with the socket 19, and 45 then axially shifted in the direction indicated by the upper arrow of Figure IV. The tube 15 is advanced until its lower end extends below the shoulders 20 defining the lower limit of the socket 19 and its flared end 18 abuts the shoulder 21 at the top of the socket 19 (see Figure III).

The supporting arm 11, as shown in the drawings, may be longitudinally slotted or bifurcated below its shoulder 21 to provide spaced branches 27 and 28 (see particularly Figure IV). Between 50 the shoulders 20 and 21, the inner sides of the branches 27 and 28 are shaped to conform to the curvature of the tube 15 and provide the opposite side walls of the socket 19. The preferred relative dimensions for the socket 19 and 55 the tube 15 are such that the latter has a close fit in the socket 19. Immediately below the shoulders 20, the branches 27 and 28 are shaped to provide a socket 25 in axial alignment with the socket 19. Below the socket 25, the inner 60 sides or surfaces 26 of the branches 27 and 28 curve outwardly in opposite directions (see Figures III and IV).

The yarn guide tube 16 is inserted in place by 65 axial movement in the direction indicated by its arrow in Figure IV. The upper end of the tube 16 is received within the space between the tube 15 and the side walls of socket 25, which frictionally engage respectively the inner and outer side walls of the tube 16. The socket 25 and the tube 15 cooperate to firmly hold the tube

16 and prevent its accidental removal during use of the yarn carrier 10 for laying yarn, but permit its ready removal by a suitable tool when tube repair or replacement is desired. The tube 16 may be removed, for example, by pressing 5 downwardly on its upper end with a small screw driver or other appropriate instrument. The tube 16 also serves to maintain the tube 15 in its proper place and prevent its accidental removal. When removal of tube 15 is desired, the tube 16 10 is first removed. The tube 15 may then be readily pushed or raised out of its socket 19. In other words, the tubes 15 and 16 are detached by axial movement in opposite directions.

The yarn guide tube 15 may be formed of 15 nickel, steel or other suitable material and is preferably of relatively rigid construction.

The yarn guide tube 16 may be of any suitable construction. The tube 16 is preferably resilient 20 and is illustrated in the form shown in Figures IV and V of my prior Patent No. 2,101,801.

A third tube 17 of wear-resisting material 25 may, if desired, be provided as a liner for the free end of the tube 16. As the yarn laying tip of a yarn carrier is preferably made as small in overall width as possible, the lower portions of the tubes 16 and 17 may be tapered as shown in Figure III. This tapering, which may be secured in any suitable manner, is preferably accomplished after the tube 17 is inserted into the tube 16 and before they are assembled in the yarn carrier 10. The tubes 16 and 17 are shown in Figure III as they appear before they are assembled together and subjected to the tapering process.

The tube 16 is made flexible to permit its deflection in event of engagement with an obstruction during yarn laying operations. If a misplaced sinker (3) is engaged during the travel 40 of yarn carrier 1, the flexible tube 16 may be deflected rearwardly and to one of the two dotted line positions illustrated in Figure III, depending on the direction of movement of the yarn carrier 10. During this deflection, the flexible tube 16 will engage and conform to the curved shape 45 of one of the surfaces 26. The engaged surface 26 causes the deflected flexible tube 16 to assume a curved shape and thereby avoids permanent deformation of the tube which might occur where the upper and lower tube portions are free 50 to assume a sharp angular relation with respect to each other during deflection of the lower tube end.

As will be seen from Figure III, the plate 12 will protect the flexible tube 16 from engagement 55 with the sinker bed 1 during rearward deflection with respect to the direction of travel of the yarn carrier 10. Under certain conditions, the flexible tube 16 may be deflected transversely of its normal direction of movement during yarn laying operations. This deflection might be caused, for example, by engagement with another yarn carrier 10. To permit this deflection, the lower central part 13 of the plate 12 is preferably removed or cut out. The cut-out 13 may 60 be omitted, however, if it is not desired.

As previously explained, each knitting section of a straight knitting machine has a number of yarn carriers, only one or two of which ride the sinker bed 1. The protective plate 12 is preferably provided for the yarn carriers 10 which ride the sinker bed 1. The other yarn carriers of the knitting section may be constructed as shown in Figures I to IV, but with the protective plate 12 omitted therefrom. that the sinker bed riding yarn carriers 10 may be constructed as shown in Figures I to IV, but with the protective plate 12 omitted. In this case, the supporting arm 11 during yarn laying operations would engage the sinker bed 1 and be subjected to the usual rubbing action.

A further embodiment of this invention is shown in Figure V. This embodiment includes the tubes 30 and 31 which may be similar in structure to the tubes 16 and 17 respectively of the other figures. The flexible yarn guide tube 30 frictionally engages and is preferably supported solely by the lower end of a yarn guide tube 32. This yarn guide tube 32, which may be formed of the same material as tube 15 of the other figures, is preferably secured permanently to the yarn carrier supporting arm 33. The tube 32, for example, may be soldered or welded to the yarn carrier arm 33. Material deposited by such soldering or welding is indicated at 34. Figure V shows only the lower portion of the supporting arm 33, and it is to be understood that the remainder thereof may be substantially the same in construction as the upper portion 25 of the supporting arm 11 of Figure I.

The tube 32 has its lower end extending below a shoulder 35 of the yarn carrier arm 33 and into the upper end of the flexible tube 30. These engaging tube portions are preferably of such relative dimensions that the tube 32 fits tightly within the tube 30 so as to prevent accidental removal of the latter, and to permit removal of the tube 30 by a suitable tool when such is desired. The tube 30, for example, may be removed by pressing downwardly on the edge of the upper tube end with a small screw driver or other appropriate instrument.

The yarn carrier arm 33 has two branches 36 and 37 extending below the shoulder 35 and at 40 opposite sides of the tube 30. The inner edges of the branches 36 and 37 may be spaced from the tube 30 as shown in Figure V and preferably have their lower portions or surfaces 38 curved outwardly in the same manner and for the same 45 purpose as the surfaces 26 of the other figures.

If the yarn carrier of Figure V is to ride the sinker bed 1 during use, it (the yarn carrier) may be provided with a protective plate similar to the one (12) shown in connection with yarn carrier 10.

The foregoing is illustrative, and it will be understood that this invention includes all embodiments coming within the scope of the appended claims.

55 I claim:

1. In a straight knitting machine yarn carrier, the combination comprising a supporting arm to have reciprocatory movement, a tubular member for laying the yarn of said carrier during 60 operation thereof, said tubular member being adapted to yield in event of engagement with an obstruction during yarn laying operations, and a yarn guide tube carried by said arm and having one end thereof disposed within said yielding tubular member to support the same.

2. In a straight knitting machine yarn carrier, the combination comprising a supporting arm, a relatively rigid yarn guide tube carried by said arm, and a removable flexible guide tube 70 frictionally secured to and carried by one end of said rigid guide tube.

3. In a straight knitting machine yarn carrier, the combination comprising a supporting arm, a substantially rigid yarn guide tube secured to said supporting arm, and a flexible guide

tube removably mounted on one end of said first-mentioned tube and frictionally gripping the same.

4. A straight knitting machine yarn carrier comprising a supporting arm, a relatively rigid 5 yarn guide tube permanently secured to said arm, and a removable flexible yarn guide tube frictionally engaging and supported solely by one end of said first-mentioned tube.

5. A straight knitting machine yarn carrier 10 comprising a supporting arm, a yarn guide tube permanently secured to said arm, a removable flexible yarn guide tube frictionally engaging and supported solely by one end of said first-mentioned tube, and means providing curved surfaces 15 for engagement by said flexible yarn guide tube during yielding movement.

6. In a straight knitting machine yarn carrier, the combination comprising a supporting arm, a yarn guide tube 20 removably carried by said arm, and a removable flexible guide tube frictionally secured to said first-mentioned tube, said tubes being detachable from each other and the said supporting arm by axial movement in opposite directions.

7. In a straight knitting machine yarn carrier, the combination comprising a supporting member having a socket and shoulders at opposite ends of said socket, a guide tube extending through said socket and having a flared end 30 supported by one of said shoulders, and a flexible tube frictionally secured to the other end of said first-mentioned tube and abutting the other of said shoulders, whereby said flexible tube maintains said combination in assembled 35 relation and may be readily removed when tube replacement is desired.

8. In a straight knitting machine yarn carrier, the combination comprising a supporting member having a socket open at both ends, a yarn 40 guide tube fitted into said socket from one end thereof and having a modified portion to prevent its complete withdrawal from the other socket end, and a yielding yarn guide removably secured to said tube and cooperating with said modified portion to releasably secure said tube in 45 said socket.

9. A straight knitting machine yarn carrier comprising a supporting member having two adjacent, axially aligned sockets, a yarn guide tube 50 supported by one of said sockets and extending into the other of said sockets, and a second yarn guide tube supported in said last-named socket.

10. A straight knitting machine yarn carrier comprising a supporting member having two adjacent, axially aligned sockets, a flexible tube having one end thereof disposed in one of said 55 sockets, a yarn guide tube carried by the other of said sockets and extending into said end of said flexible tube, said yarn guide tube cooperating with said flexible tube socket to support said flexible tube by frictional engagement therewith.

11. The combination with a straight knitting machine yarn carrier adapted to ride the knitting machine sinker bed during yarn laying operations and having a yielding yarn guide to lay the yarn, of a protective plate secured to the underside of said yarn carrier adjacent said guide for engaging said sinker bed during use of 65 said yarn carrier, said protective plate having a cut-out portion opposite the tip of said guide to permit yielding movement thereof transverse to the direction of yarn carrier travel.

12. A straight knitting machine yarn carrier 75

- comprising a flexible yarn guide tube for laying yarn on the knitting machine sinkers, and means providing curved surfaces for engagement by said flexible yarn guide tube upon deflection by an obstruction in its path of movement.
13. In a yarn carrier for straight knitting machines, the combination comprising a supporting arm having a bifurcated end portion to form two branches, the outer ends of the adjacent edges of the said branches being outwardly and oppositely curved, and a resilient yarn guide tube extending between said branches and beyond the lower extremities thereof, said tube being secured at its inner end to said arm with its other end free to yield and conform to the curvature of one of said branch edges as the tube flexes upon engagement with an obstruction during yarn laying operations.
14. In a straight knitting machine yarn carrier, the combination comprising a supporting arm member, a yielding yarn guide tube extending both inwardly and outwardly of an end of said member, and means carried by said member and frictionally engaging said tube to maintain normally the tip thereof in proper position for discharging yarn, said tube being detachable by axial movement in the direction away from said engaging means and supporting member.
15. In a straight knitting machine yarn carrier, the combination comprising a supporting member, a yarn guide tube of substantially cylindrical shape throughout and having at least a portion thereof of flexible construction in the form of coiled wire, and means carried by said member and frictionally engaging the side surfaces of said tube to maintain normally the tip thereof in proper position for discharging yarn, said tube being detachable by axial movement in the direction away from said engaging means and supporting member.
16. A straight knitting machine yarn carrier comprising a supporting arm, a relatively rigid yarn guide tube carried by said arm, and a yielding tubular yarn guide element supported by said guide tube.
17. In a straight knitting machine yarn carrier, the combination comprising a supporting arm, a yarn guide tubular element carried by said arm, and a flexible guide tube carried by said element, said yarn guide tubular element extending into and frictionally engaging said flexible tube to detachably support the same.
18. In a straight knitting machine yarn carrier, the combination comprising a rigidly mounted and relatively rigid yarn guide tube, and a flexible yarn guide tube depending from said relatively rigid guide tube, said tubes being detachably connected to each other by concentrically arranged, adjacent end portions thereof with the rigid guide tube extending into said flexible tube.
19. In a yarn carrier for straight knitting machines, the combination comprising a supporting arm having a bifurcated end portion to form two branches, the inner edges of said branches being outwardly and oppositely curved, and a resilient yarn guide tube carried by said arm and positioned between said branches, said tube being free to yield and conform to the curvature of one of said branch edges as the tube flexes upon engagement with an obstruction during yarn laying operations.
20. In a yarn carrier for straight knitting machines, the combination comprising supporting means, a resilient yarn guide tube carried by said means, and means providing a curved surface adjacent said guide tube for engagement thereby during yielding movement of the tube toward the curved surface, said curved surface having such shape as to avoid abrupt bends in the tube when in engagement therewith.
21. A yarn carrier for reciprocating movement in a straight knitting machine to lay yarn along the sinkers and needles thereof, said yarn carrier comprising a supporting arm, a flexible tube carried by said arm for laying yarn relatively close to said sinkers and needles and adapted to yield rearwardly with respect to the direction of travel of the yarn carrier in event of the tube striking an obstruction during yarn laying operations, and means providing curved surfaces at opposite sides of said flexible tube for engagement thereby during rearward yielding movement of said tube in either direction of travel of said yarn carrier, whereby said tube in flexing conforms to the curvature of one of said surfaces and abrupt bends in said tube during yielding movements are avoided.
22. The combination with a straight knitting machine yarn carrier adapted to have its lower end ride a knitting machine sinker bed during yarn laying operations, of a relatively thin means secured to said yarn carrier end to space slightly the same from the sinker bed and to take all the wear caused by the sinker bed during travel of said yarn carrier, said means being of such size and shape as to provide an increase in surface area for sliding contact with said sinker bed.
23. The combination with a straight knitting machine yarn carrier adapted to have its lower end ride a knitting machine sinker bed during yarn laying operations, of a relatively thin plate secured to said yarn carrier in such position as to take all the wear caused by the sinker bed during travel of said yarn carrier, said plate extending beyond the tip of said yarn carrier to provide a surface of increased area for sliding contact with said sinker bed.
24. The combination with a straight knitting machine yarn carrier adapted to have its lower end ride a knitting machine sinker bed during yarn laying operations, of a relatively thin and flexible metallic protecting plate secured to the underside of said yarn carrier so as to engage said sinker bed and take all the wear caused thereby during yarn laying operations of said carrier, said metallic plate extending laterally beyond the tip and side edges of said yarn carrier to provide an increase in surface area for sliding contact with said sinker bed.
25. In a straight knitting machine yarn carrier, the combination comprising a supporting member, a yarn guide of substantially tubular shape and having at least a portion thereof of flexible construction in the form of coiled wire, and means carried by said member and frictionally engaging the side surfaces of said guide to maintain normally the tip thereof in proper position for discharging yarn in knitting operations, said tube being detachable by axial movement in the direction away from said engaging means and supporting member.

FRANK G. WEISBECKER.

CERTIFICATE OF CORRECTION.

Patent No. 2,214,712.

September 10, 1940.

FRANK G. WEISBECKER.

It is hereby certified that error appears in the printed specification of the above numbered patent requiring correction as follows: Page 1, first column, line 10, for the word "yarns" read --yarn--; line 13, for "2,201,801" read --2,101,801--; and that the said Letters Patent should be read with this correction therein that the same may conform to the record of the case in the Patent Office.

Signed and sealed this 8th day of October, A. D. 1940.

(Seal)

Henry Van Arsdale,
Acting Commissioner of Patents.
